SEISMOGRAPHIC PROSPECTING APPARATUS FOR DIRECTING EXPLOSIVE ENERGY

Norman B. Blake, Beaumont, Tex., assignor to Sun Oil Company, Philadelphia, Pa., a corporation of New Jersey.

Application November 20, 1945, Serial No. 629,728

4 Claims. (Cl. 181—5)

1

My invention relates to seismographic prospecting, which comprises detonating an explosive at or below ground level and recording at distant points the propagated waves of refraction and reflection.

The object of my invention is to confine within practicable limits the propagation of the waves in a generally downward direction so that, within practicable limits, the detectors will record mainly waves reflected from a subsurface layer lying beneath the locus of explosion. This object is in large measure obtained by my invention, in which the total energy of the explosion is so directionally controlled as to increase the energy downward to the reflecting horizon with a corresponding substantial diminution of energy expended in other directions. To the extent that this object is accomplished the amount of energy reflected to the detector will be substantially larger than that received from other or random paths, thereby enabling the reflected layer to be more readily identified by observing the increased amplitude on the record.

It follows, also, that this concentration of explosive energy in a generally downward direction, especially in difficult areas, will change the frequency spectrum of the energy received by the detectors, which change often produces an improvement in the recorded reflections.

It follows, also, that any concentration of energy in a given direction will more effectively penetrate any hard strata lying in such direction.

While the attainment of the above objects is not dependent upon the employment of the specific construction shown in the drawing, such construction is well adapted to the practice of the process embodying my invention. The drawing is a vertical section through such a construction.

In a shot hole *a*, which may have any selected depth, preferably between 10 and 125 feet, is inserted a cylindrical casing *b*, preferably of high strength steel, the lower part of which has a relatively thick or reinforced wall *c*. In the lower part of this casing is inserted an explosive charge *d*. The length of the thickened portion of the casing wall somewhat exceeds the length of the explosive charge. Provisions are made to oppose resistance to discharge of explosive energy in an upward direction. One way of doing this is to fill the shot hole with liquid *e*, conveniently water, to provide a liquid column overlying the explosive and adapted to absorb the reaction of explosion. It is desirable, but may not be necessary, to provide beneath the ex-

2

plosive charge an open space *f* the upper part at least of which is surrounded by the casing, the thick wall of which is preferably tapered at its end as shown. To avoid the filling of this space with water from the column *e*, the space *f* may be occupied by a thin walled empty container *n* affording no effective resistance to the force of explosion.

The explosive charge is lowered into the casing by means of cap wires *g*, which also lead to the blasting cap (not shown). The cap wires are secured at their upper ends to a cross bar *h* which may rest on the top of the casing *b*. The explosive charge is thereby suspended in the casing and its vertical position therein accurately fixed. Connected with the upper end of the cap wires is a lead *i* (which may be an extension of the cap wires *g*) to the blasting machine (not shown). The casing may be suspended from a rope *k* having at its end a ring *m* closely grasping the upper end of the casing. This rope should be subjected to a strong pull to hold the casing stationary during the moment of exploding the charge.

25 When the explosive charge is detonated, the casing *b* functions in a manner similar to that of a cannon and, seeking the line of least resistance, the explosive energy is directed largely in a downward direction. While the distribution 30 of the energy of explosion is in all directions, the amount of shot energy in a directly downward direction and in oblique directions having relatively small angles to the vertical is dominant, or, more accurately expressed, greater than that obtainable from a shot of equal size free 35 to distribute its energy equally in directions varying between vertical and lateral.

Since the energy of an unconfined explosive charge is effectively discharged equally in all 40 directions, it will be understood that a casing of practicable maximum weight, unless very short, would have its wall so thin that it would be penetrated by the lateral discharge of explosive energy. By substantially thickening, by reinforcement 45 or otherwise, the part of the casing wall that encloses the explosive, rupture of the casing by the shot energy directed in a horizontal direction and in directions having relatively small angles to the horizontal is prevented. It is practicable to make the entire casing of high strength 50 steel, the thickened lower end being then an integral part of the casing; or the extra thickness of this part of the casing may be secured by reinforcing the casing in any known manner. The thickened casing wall being effective to protect

the casing from rupture, the part of the explosive energy that would otherwise be discharged laterally is diverted downward through the less resistant body of liquid below the explosive charge or, if an air space below the charge is provided, through a body of air whose resistance to the discharge of explosive energy is very slight.

What I claim and desire to protect by Letters Patent is:

1. Seismographic apparatus for directing explosive energy in boreholes within the earth comprising a borehole casing, an explosive charge suspended within and above the bottom of the casing and a substantial distance above the bottom of the borehole, the part of the casing enclosing the explosive charge being of substantially greater thickness than the remainder of the casing, a readily disruptable member closing the bottom of the casing, and a liquid column resting on said member and extending to a substantial distance above the explosive charge.

2. Seismographic apparatus for directing explosive energy in boreholes within the earth largely in a general downward direction comprising, in combination: a casing inserted in and above the bottom of the borehole; an explosive charge suspendable in said casing above the bottom of the borehole; a liquid tamping column in the casing extending a substantial distance above the explosive charge; and a member substantially non-resistant to the force of explosion and sealing the lower end of said casing against down-flow of tamping liquid into the bottom of the borehole.

3. The apparatus defined in claim 2 in which the wall of said casing, for a limited vertical distance opposite the locus of suspension of the explosive charge, is of a thickness substantially greater than that of the main body of the casing wall.

4. The apparatus defined in claim 2 in which the casing has a flared mouth in the lower end thereof and in which the sealing member is a hollow plug and is seated in said mouth.

NORMAN B. BLAKE.
